Application June 3, 1938, Serial No. 211,645
In Great Britain June 17, 1937

10 Claims. (Cl. 179—5.5)

This invention relates to telephone systems and to apparatus for use in connection therewith for the purpose of enabling signals, codes or messages to be transmitted over the line and recorded.

The chief object of the invention is to provide a simple and efficient means which can be utilised for the purpose of advising a subscriber, upon his return, of the fact that he has been called during his absence from the home, office or other building in which his telephone is located.

A further object of the invention is to provide a simple and efficient means adapted to insure that, when a call is unanswered, a record will be made of the caller's number and/or his message upon means provided for the purpose at the called-subscriber's end.

According to the invention each subscriber or certain subscribers is or are provided with means adapted to be brought into operation automatically or by manually operable means for transmitting along the telephone line a predetermined signal or group of signals having characteristics which render them capable of being recorded and identified at the receiving end by a subscriber who is not available at the time of the call.

The invention may be carried into effect in various ways and, in its simplest form, it comprises means located at the sender's end of the line adapted automatically to transmit over a line a signal or signals which is or are characteristic of the sender's telephone number or telephone number and exchange and means located at the receiver's end for receiving such signals and making a record of the same.

In the preferred embodiment of the invention, the sending end of the line is equipped with an oscillatory, rotary or other movable member adapted to influence the character of a series of electrical impulses transmitted along the line so as to render them characteristic of that particular sender's identification number or of his number and exchange area. The aforesaid movable member may be arranged so that it is adapted to be brought into operation immediately the sender lifts his receiver or after a predetermined delay period. Alternatively, the arrangement may be such that the movement of the said member or the commencement of its movement is under the control of the sender. The character of the impulses may be varied by varying the nature of the movement imparted to the movable member or provision may be made for utilising different portions of the movable member or of its movement for obtaining the varied impulses.

The aforesaid member may be preformed or shaped to enable the same to be utilised for the purpose in view and may comprise a rotary member or drum the peripheral surface of which comprises parts having differing electrical conducting characteristics, e. g. conducting and insulating parts, formed to correspond with, or to formulate signals which correspond with, the characteristics of the elements or digits of the signal, telephone number or message to be transmitted.

At the receiving end of the line, there may be provided a record sheet or strip and means such as a marker, perforator or the like for co-operating therewith to produce a record from which the signal or message can be identified. For example, means such as a solenoid may be provided at the receiving end of the line and the arrangement may be such that each time an impulse is produced at the sending end, the solenoids will be brought into operation to cause the marker, perforator or the like to function. The record sheet or the like may conveniently be carried by a drum and, if desired, means may be provided for enabling the drum to be rotated in a step-by-step manner during or at the termination of each movement of the oscillatory member at the transmitting end.

In order that the said invention may be clearly understood and readily carried into effect, the same will now be more fully described with reference to the accompanying drawings which illustrate diagrammatically various circuit arrangements suitable for adoption at subscriber's stations required to be equipped with means for enabling the invention to be carried into effect.

Figure 1 is a schematic view of a portion of a telephone circuit embodying the present invention.

Fig. 2 is a diagrammatic side view of an impulse transmitting mechanism.

Fig. 3 is a diagrammatic side view of an impulse recording mechanism.

Fig. 4 is a modified form of impulse transmitting and receiving mechanism.

Fig. 5 is a view similar to Fig. 1 of a modified circuit.

Fig. 6 is another view similar to Fig. 1 of a further modified circuit.

Fig. 7 is another view similar to Fig. 1 of still another modified circuit.

Fig. 8 is still another view similar to Fig. 1 of a still further modified circuit.

In Fig. 1 of the accompanying drawings, A indicates one side of a telephone transmission line and B indicates the other side thereof. Also C

indicates the subscriber's bell arranged in the usual ringing circuit which may be earthed at E, or as in some cases, may return via the line B. In the ringing or other warning circuit is arranged 5 a pair of relays or electro-magnetically operable units a and b, one of which is adapted, when energised, to open a normally closed switch c whilst the other is arranged so that when it is energised, it is adapted to attract one end of a 10 switch lever d, which may be normally in the off position, and to cause the same to move about its central pivot and to engage a contact e arranged in series with an electro-magnetic device G which forms a part of an impulse recording mechanism. 15 The switch c, the electro-magnetically operable unit b and the midpoint of the switch lever d are also joined in series by a lead f the other end of which is connected with a suitable point in the subscriber's receiver or receiver cord g, or to a 20 convenient point on the line B. Hence it will be seen that, upon energisation of the subscriber's ringing or warning circuit the switch c will be opened and the lever d will be moved into contact with the contact e, thus allowing the bell C to 25 function in the normal manner. Immediately, however, there is a pause in the ringing or warning signal, the switch c will close again. In comparison with unit a, the unit b is relatively slow acting with the result that the lever d will for a 30 short period remain in contact with e after the switch c has closed again. During this period, a circuit through the called subscriber's receiver, his lead f and the electromagnetic device G of his impulse recording mechanism is closed and 35 such circuit is connected through the line and the exchange with the calling subscriber whose impulse transmitter is now connected in the circuit through his switch d which may be closed by manually operable means. At this stage, the two 40 subscribers are interconnected through the exchange in the same manner as when the line is available for speech currents so that as the calling subscriber's impulse transmitting mechanism is actuated, the called subscriber's recording 45 mechanism is caused to function for recording purposes. Hence, it will be seen that the invention provides a simple and convenient arrangement for enabling the ringing or other warning current to prepare the called-subscriber's circuit 50 arrangement to be connected, either immediately or through the usual exchange connections, with the calling subscriber for transmitting, receiving and for recording, and to enable the same to be brought into operation for recording during the 55 pauses in the different phases of the ringing or other warning signal so long as the latter is continued. Alternatively, the relays may be arranged and the circuit arrangement varied so that the recording circuit is prepared for functioning by 60 the operation of the ringing or other warning signal and the latter prevented from continuing to function until the message has been completed. According to another alternative arrangement, the relays and other elements may be arranged 65 so that the recording is caused to take place at the same time as the functioning of the bell or other warning signal.

The impulse recording mechanism and the impulse generating mechanism may comprise a V-shaped or hair-pin like member pivotally mounted 70 at K and having an armature 150 and two downwardly extending arms H and L arranged for movement over the surfaces of two rotatably mounted drums P and Q. The recording arm L 75 may be provided with a suitable marker arranged

so that, when this arm is attracted by the electro-magnetic device G and the arm is caused to move out of its normal plane of movement, the marker will be brought into contact with a sheet of paper or the like carried by the drum Q. 5

The drum P may be provided with parts of differing electrical conducting characteristics, e.g. conducting and non-conducting areas or strips for the purpose of enabling the arm H to generate or formulate signals which are characteristic of 10 the sender's telephone number or other signal to be transmitted and, upon the closing of the receiver's switch c, which thus signals the exchange whereupon the usual connections between the two subscribers are made, the impulses being 15 formulated by the sender's drum P and its associated arm H will pass to the device G of the impulse recorder of the called subscriber's instrument to actuate the marker carried by the arm L as the latter moves across the strip carried by the 20 drum Q in synchronism with the movement of the arm H at the calling subscriber's end of the line. For the purpose of enabling the two V-shaped or hair-pin like members to step over the non-conducting areas, each may be provided 25 about its pivotal support with an upwardly and/or downwardly extending arm terminating in an adjustable weight W on a spring and the said arm or another arm coupled therewith may be utilised as the armature of an electro-magnetically 30 operable device consisting, as shown in Fig. 1, of two electro-magnets F and F' which are also so arranged and connected in circuit that they are adapted to be actuated by the impulses being generated or formulated by the calling subscriber. 35 That is to say, at the called subscriber's end, the impulse recorder and the electro-magnets F and F' are connected for intermittent operation in series with the line that carries the impulses being formulated by the calling subscriber, the 40 said electro-magnets being actuated alternately. The movements of the mass W allows its equivalent mass L time to change its plane of oscillation and enables it to rise and fall relatively to the paper or the like on the drum Q. This arrangement also ensures the breaking up of a magnetic pull into several stages corresponding to the conducting and insulating areas which are included in the circuit. Synchronisation is also ensured by arranging the circuit as shown so that 45 the pull of the electro-magnetic device G on the arm L is simultaneous with the action of the electro-magnet F or F' on the armature 150 and persists as long as the calling subscriber's arm H is traversing one of the conducting portions of 50 his drum P. 55

In Fig. 2 of the drawings there is shown diagrammatically a side view of the impulse transmitting mechanism shown in Fig. 1 and Fig. 3 shows diagrammatically a side view of the impulse recording mechanism. In the arrangement shown in Fig. 1, the drums P and Q are adapted to be rotated by a toothed or ratchet wheel N disposed intermediate the ends of a rotary member which incorporates the two drums. If desired, however, this arrangement may be replaced by one in which the two drums are adapted to be rotated by a toothed or ratchet wheel disposed at one end of one of the drums as is shown, for example, in Fig. 4, the arrangement being such that 70 the ratchet wheel N is adapted to be rotated step by step by a pawl associated with the armature 4 of an electro-magnetically operable device 5. The latter may be connected in circuit with a flexible contact device 7 arranged so that the lever 75

H or L contacts with the contact device at the beginning or end of its swing and so energises the electro-magnetically operable device 5 to attract the armature 4 and to thus turn the ratchet wheel 5 through one step.

Referring now to Fig. 5 of the accompanying drawings, it will be seen that the subscriber's bell C is arranged in the usual ringing circuit and that a ringing tone circuit is provided across the lines A and B by the conductors 161, 162, 163, 164 and 165. Included in said circuit, is the electro-magnetically operable unit b adapted, when energised, to attract one end of the switch lever d pivoted at 8 and adapted when so attracted, to engage the contact e. The latter is connected by a conductor 12, which includes an A. C. relay E, with another contact 14 which is normally engaged by a switch lever 151 which is in turn, connected by a conductor 15 to the pivotal mounting 18 of an impulse recording mechanism which is similar in many respects to that described above in that it comprises a V-shaped or hair-pin like member pivotally mounted at 18 and having two arms H and L arranged for movement over the surfaces of two rotatably mounted drums P and Q. The recording arm L may be provided with a suitable member arranged so that, when an armature 20 is attracted by an electro-magnetic device G, the arm will be caused to move out of its normal plane of movement and the marker will be brought into contact with a sheet of paper or the like X carried by the drum Q.

The mechanism also includes a weighted lever or pendulum W (which is preferably flexible or resilient) depending from the pivotal mounting 18 and arranged for movement with the V-shaped or hair-pin like member and the lower end of the pendulum is provided with an extension serving as a contact 24 for engagement with a switch member 25 which may conveniently consist of a disc or ring-like element provided with a circumferential cut-away portion or recess and suitably biassed so that one side of the cut-away portion bears against the extension of the pendulum. The biassing may be accomplished by suitably weighting the switch member or by mounting the same eccentrically or by other means. Through the medium of the pendulum and its contact 24, the conductor 15 is electrically connected with one side of the said cut-away portion which is connected by a conductor 26 with an electro-magnetic device F' and the latter is connected with the other side of the line B.

Hence, it will be seen that upon contact being established between the switch lever d and the contact e, a circuit is completed through the conductor 30, switch lever d, A. C. relay E, switch lever F, pendulum W and electro-magnet F' to the line B and current traversing this circuit will energise the electro-magnet F' thereby attracting its armature 150. The latter is pivoted at 18 and interconnected with the hair-pin like member so that the arm L is swung to one side of the sheet of paper X ready for operation.

It will also be observed that from the contact e is arranged a circuit parallelling that containing the A. C. relay E, the switch lever 151 and the conductor 15, said circuit including a switch 34 adapted to be closed by the relay E, a relay 35 for opening the switch 151 and the electro-magnetic device G. Hence, when an alternating or pulsating current derived from the exchange or sender's apparatus traverses the circuit containing the A. C. relay E, the latter will be actuated

to close the switch 34 and the marker will be brought into its marking position. Also, by virtue of the energisation of the relay 35, the switch 151 will be actuated to open the direct current circuit through F'. 5

Each subscriber is provided with an impulse generating device for formulating impulses which are characteristic of his telephone number or other signal to be transmitted and this device may comprise a drum P provided with a central 10 continuous conducting strip or ring 40 and with two end continuous conducting strips or rings 41 and the intermediate portions may be formed with conducting and insulating areas or strips which are so arranged that, by the movement of 15 the arm H thereacross in synchronism with the movement of called subscriber's recording arm L, impulses which are characteristic of the sender's telephone number and exchange lettering or other signal to be transmitted are formulated. Intermittent movement of the drums P and Q is adapted to be brought about by a pawl and ratchet wheel N or other suitable means such as is described above through the actuation of the electro-magnetically operable device 5 brought 20 into operation at the end of each swing of the marking arm L. When impulses are to be transmitted over the line, the switch lever d is moved by automatic or manually operable means so that its upper end is brought into contact with 30 the contact 46 which is connected with the drum P through an A. C. relay 48.

From the foregoing it will be seen that when the lower end of the switch arm d at the called subscriber's station is in contact with the contact e, a D. C. circuit is closed through the switch 151 and the electro-magnet F'. The current for this circuit may be derived from the central exchange or from a local source or battery adapted to be brought into operation by an exchange current and when this current is available and utilised for the actuation of the magnets F' and the consequent displacement of the hair-pin like members, the pendulums W will also be displaced in opposition to the biassing means associated with the switches 25 and the arm H will be moved from contact with the conducting zones 40. The momentum of the pendulum device is sufficient, however, to carry the calling subscriber's arm H over the nonconducting area to contact with the next conducting area formed, e. g. by one of the digits of the telephone number, with the result that the calling subscriber's mechanism formulates impulses varying in character with the nature of the telephone number, which impulses intermittently actuate the device G at the called subscriber's instrument for effecting the recording. Thus the circuits including the relays E and 35 will come into operation alternately as the calling subscriber's arm H is advanced across the impulse formulating drum. In this way, the switches 25 are eventually brought into a position in which the biassing means causes the contact 24 to be broken and the opposite side of the recess of the switch contacts with the pendulum device 45 to bring the other electro-magnet F into operation with the result that movement of the hair-pin like members and the pendulum device will be reversed. In the arrangement illustrated, an armature 51 is attached to the recording arm L 50 and 52 is a contact carried by the switch 25 for engagement with a relatively fixed stop and contact 53. When the contact 24 has swung its full period to the right the electromagnetic unit 5 operates to hold the armature 51 in position also 55

the member 55 carrying the pawl associated with the ratchet wheel N. Also, when the calling subscriber's arm H reaches the corresponding position the contacts 24 and 52 and the contacts 52 and 53 on his instrument will make and/or break and thus send across the inductive coupling a pulsation to operate the relay E at the called subscriber's instrument. The relay 35 is thus brought into operation to open the circuit 15, 56, 54, 53 and to de-energise the unit 5 to release armature 51 to enable the hair-pin like member to swing back and also to release armature 4 to rotate the drum Q. If the calling subscriber's arm H arrives first and is held, through its armature 51 by its electro-magnet 5 the subsequent arrival of the called subscriber's arm L and the make and/or break operations will send back its pulsation to be received by the caller, via conductor 30, 8, 46, 48 opening 58 and thus restoring electromagnet 5 and securing synchronism for the rotation of the drum.

It will be observed that when the electro-magnetic unit b is actuated to cause the switch lever d to engage with the contact e, it has the same effect for completing subscriber's loop as if the receiver had been lifted and this flashes a signal to the exchange to connect the two subscribers in the usual way. On completion of the message, the relatively conducting and insulating areas will flash the clearing signal.

The invention can be adapted to various forms of transmission lines or circuits whether wired, inductively coupled or radio-linked, the number, position and character of the various electrical units, e. g. inductances, relays, capacities and the like, incorporated in the system being varied to suit the individual requirements. For example, in order to carry into effect some of the objects of the invention, e. g. the transmission reception and/or recording of electrical impulses, when the operator is not available, over a metallic and/or an inductively coupled line or circuit including radio-linked means of communication, the switch lever 34 may be arranged so that it is normally in engagement with its contact, and the switch lever 151 may be arranged to be normally free from its contact 14 (as is shown, for example, in Fig. 6 of the accompanying drawings). With such an arrangement when the bell 50 (or other warning device) current or impulse operates the relay b battery current will flow from the line A, through 30, b, 8, d, e, 34, 35, G and back via the B line. The relay 35 will then operate the switch lever 151 and battery current 55 will flow through e, 12, E, 14, 151, 15, 18, W, 24, 26, F' and back via the B line, both F' and G functioning.

Now, if the parts H and P of the calling device are in metallic circuit, every time the part H 60 breaks circuit in the calling device, the devices G and F' restore in the called device.

But when the two devices are inductively coupled then the interruptions of contact through H and P in the calling device are received as 65 pulsations, or alternating current impulses by E, which opens 34, restores 35, opens 151 and both F' and G at the called end restore.

Thus the lateral movements of the respective hair-pin members are synchronised and the 70 sender's makes and breaks are registered by the called subscriber's device in the proper order.

As shown in Fig. 6, for synchronising the rotary movements of the drums, or the sliding and the like movements of any of the other displaceable 75 elements, in both a metallic and a non-metallic

circuit, the electro-magnetic device 48 in the calling device may be a D.C. magnet and be connected through a normally closed switch lever 69 to the drum P. The device 48 controls a normally open switch lever 58 in circuit with an A. C. relay controlling the switch lever 60. Also, 53 may be a flexible or a relatively movable contact, and 41 may be a relatively large conducting area. Thus, in the calling device, the upper part of arm d having contacted with 46, D. C. current operates 10 F' then F, until 24 contacts 52 and 53 being movable or otherwise, offering a means of relative long contact battery current will flow from the A line through 8, 46, 48, 60, 40, 41, H, 18, W, 24, 52, and F to the B line. At the same time, battery current will also flow through 46, 58, 61, 57, 56, 54, 53, 52, F, B line, B line in the called device, F, 52, 53, (if 52 has already arrived to contact with 53) 54, 57, 56, 15, 151, E, 12, e, d, 8, b and 30 to A line. The electromagnetic device 5 then 20 operates to hold 4 and/or 51, until W swings back and breaks and/or reverses the contacts. If 52 reaches 53 in one device in advance of the other, 5 cannot operate but a period of waiting is provided for, by 41, H in the calling device 25 and 52 and 53 in the called device.

When the devices are coupled inductively or radio-linked then when 52 reaches 53 in either device 5 will hold 51, and 4 until a make and/or a break pulsation is received from the other device to operate in the calling device 57 open 60 restore 48 and open 58 thus restoring 5 and in the receiving device the pulsation operates E opening 34, restoring 35 and opening 151 thus, too, restoring 5, the pulsations operating both 35 ways.

In the above arrangements, the unit b may comprise an A. C. and/or a D. C. relay suitable both for causing d to engage with its proper contact and to hold the same engaged. Also, in some instances, a photo-cell or similar device may be provided for the purpose of engaging d and its associated contact.

Means may also be provided for marking or recording incoming and/or outgoing calls. For 45 example, the G unit and 35 may be connected with a contact that is brought into circuit only when the arm H and/or the arm L or other movable element reaches that contact.

Means may also be provided for registering 50 only the effective calls, whether incoming or outgoing, irrespective of whether the device is in use at the other end or not. For the purpose, a lead may be taken from G and 35 to a contact disposed between 52 and 53 and this contact 55 arranged to be brought into the circuit only when 52 is caused to engage with 53.

Also, the recording drum or sheet X may be provided with number graduations to facilitate the reading of the registration or checking marks. 60 If desired, an alarm signal or warning mark may be associated with X or elsewhere for indicating or warning of the approach of a condition in which the marking means needs attention.

In its preferred form, the invention also includes means for enabling a calling subscriber to determine or be advised as to whether the correct number has been obtained and said means may be actuated or adapted to be brought into actuation by mechanical or electrical means. For 65 this purpose, each of the drums P may be arranged so that it is capable of being adjusted angularly and each drum may carry a cam or other means capable of establishing contact at 70 46 and breaking the contact between d and e 75

once the unit *b* has brought *d* and the cam within reach of one another. Thus, when the calling subscriber lifts his receiver and obtains a number, he will be able to hear the clicking sounds or notes produced by the functioning of the called subscriber's device and on the approach of the signalling section of the device (which may be preceded by special interruptions on the drum) he can switch-in his device (if necessary after adjustment) to have the called number marked on his recording element *X*. If this number should be the wrong one he then may have it cancelled in the usual manner.

Referring now to Fig. 7 of the accompanying drawings, it will be seen that the subscriber's bell *C* is arranged in the usual ringing circuit and that the subscriber's circuit includes a device *200* incorporating sensitive pivotally mounted pointer or switch *205* which normally rests against a relatively fixed contact *201* and which, upon displacement, is adapted to engage another relatively fixed contact *202*, the pivot being connected with one side (e. g. the side *A*) of the transmission line. Associated with the device *200* are an ear piece *206* and a microphone *207*, the latter being arranged in close proximity to the former and being connected in circuit so that pulsations received by the ear piece will affect the microphone to cause the latter to influence the device *200* in such a manner that the pointer or switch *205* will be caused to be displaced from the contact *201*, towards or to the contact *202*, such movements being in sympathy with or forming a reproduction of impulses received over the line. If desired, a battery *89* or other source of local current may be arranged in circuit with the device *200* or the apparatus.

In one side (e. g. the side *B*) of the line is arranged the coil of a slow release relay *b* adapted, when energised, to displace the switch member *d* pivoted at *8*, said member in this embodiment comprising three arms indicated at *d*, *d1* and *d2*.

The subscriber's station also includes an impulse recording mechanism which is similar in many respects to those described above and comprises a V-shaped or hair-pin like member pivotally mounted at *18* and having two arms *H* and *L* arranged for movement over the surfaces of two rotatably mounted drums *P* and *Q*. The recording arm *L* may be provided with an armature *20* opposite which is disposed an electro-magnetic device *G* which when energised will cause the arm to move out of its normal plane of movement so that a marker *M* or the like provided at the end of the arm will be brought into contact with a sheet of paper or the like *X* carried by the drum *Q*. The electromagnetic device *G* is preferably carried by means also pivotally mounted at *18* and adapted to move about the pivot in synchronism with the arm *L*. As will hereinafter appear, the arm *L* is adapted to be moved about the pivot *18* to cause the marker or the like to move across the paper *X* and the arrangement is preferably such that the arm is displaced in one direction (e. g. to the right) by the actuation of an electro-magnet *F'* when it attracts an armature *150* carried by the aforesaid V-shaped or hair-pin like member and is adapted to be displaced in the opposite direction under the influence of gravity. During the periods when the arm is required to be moved by gravity, it may be desirable to provide means for arresting its movement about the pivot *18* whilst the marker is in contact with the paper and, for

this purpose, there may be provided adjacent the opposite end of the electro-magnetic device *G* which end may be slow to release, a fixed but flexible metallic member adapted, upon energisation of *G*, to be attracted and flexed by *G* in such a manner that both *G* and the arm *L* will be momentarily prevented from movement about the pivot *18*.

The aforesaid drum *P* forms part of an impulse generating device for formulating impulses which are characteristic of a telephone number or other signal as is described above, the said drum is provided with conducting and insulating areas or strips which are so arranged, that by the movement of the arm *H*, thereacross in synchronism with the movement of called subscriber's recording arm *L*, impulses which are characteristic of the sender's telephone number and exchange lettering or other signal to be transmitted are formulated.

Synchronism of the respective markings at one end of the line with the corresponding impulses generated at the other end is brought about by the functioning of the respective relays and their associated contacts, and the consequent functioning of arresting means for the arms *H* and *L* as hereinbefore described. Intermittent movement of the drums *P* and *Q* is adapted to be brought about by the pawl and ratchet wheel *N* or other suitable means such as is described above through the actuation of the electro-magnetically operable device *5* brought into operation at the end of each swing or during the swing in either direction of the marking arm *L*. When impulses are to be transmitted over the line by the calling subscriber, the switch lever *d3* is moved by automatic or manually operable means so that its lower end is brought into contact with the upper end of the lever *d1*, and *d1* swings so that *d* is contacted with *46* or *e*.

It will be seen that, when a subscriber is called, alternating current can pass from one side of the line, e. g. *A* through the bell or other warning device *C*, capacity *C'* and the coil of the slow release relay *b* to the other side of the line. The effect of such a ringing current through *b* is to cause the switch lever *d1* to be swung about the pivot *8* to the left and also to close the switch *4*. Closing of switch *204* by-passes *b* and allows the bell to ring without deleterious effect. Also, by the movement of *d1*, the lever *d* will be raised to engage either a contact *e* or a cam *46* carried by the shaft carrying the aforesaid drums. When the lever *d* contacts with the contact *e* or with the cam *46*, the circuit is completed through conductor *15*, contact strips *82* and *83*, arm *H*, plate *225*, and the coil of the electro-magnet *F'* to the other side of the line, thus providing a path for alternating current or pulsations.

The ringing current is now capable of influencing device *200* and its sensitive element *205*, which will move to contact *202*, and a solenoid *E* will operate closing by-pass switch *86* to form a path for D. C. and thus trip the ringing current circuit. (*E* may be of an inductance and/or resistance that will allow ringing current to continue functioning.) The calling subscribers can now hear the called station apparatus function and may operate his switch *d3* to start his apparatus and receive and/or transmit signals. Solenoid *E* may also be slow to operate and thus switch element *205* may have to be moved to *202* more than once to close *86*. Alternatively, it may be arranged, e. g. in metallic circuits, for the ringing current to continue until the calling sub-

scriber realising that the called subscriber is not answering operates his impulse transmitter or closes his switch *d*3 to bring his transmitting apparatus into operation. By the act of switching at the calling subscriber's end of the line, the ear piece 206 and microphone 201 at the called subscriber's station as well as those at the calling station if so equipped will be brought into operation so that the sensitive pointer or switch element 205 will be momentarily swung into contact with the contact 202 to close direct current circuit from one side of the line (e. g. A), through 205, contact 202, a slow release solenoid E, conductor 91, electromagnetic device G and conductor 92 to the other side of the line. Thus the solenoid E is brought into operation to hold the levers *d*2 and *d* tilted with the latter in contact with *a*6 or *e*. Also, by the operation of E, switch 86 is actuated to by-pass condenser 85 at the called station and thus closing another D. C. circuit and by the operation of G, the armature 20 is attracted to cause the marker M to be brought into contact with the paper X. Having thus set up the D. C. circuits referred to and as soon as switch element 205 returns to contact with 201, the direct current passing through F' operates the latter to cause H and L to swing to the right about the pivot 18, the swinging movement continuing until L reaches its other extreme position.

Shortly before the marking arm L reaches the end of its swinging movement to the right, contact takes place between an element 52 carried by the arm, a switch 58 and a contact 53 with the result that the circuit is closed from A through 205, 201, switch 86, lever *d*, conductors 12 and 15, conductor 56, coil 54 of the electro-magnetic device 5, contact 53, switch 58, coil of the electro-magnetic device 79 to the other side of the line. Electro-magnetic device 5 is thus operated and attracts the armature 51 on the arm L and is at this stage of the operation in close proximity to the device 5. Also, the downwardly extending portion of the electro-magnetic device 5 attracts the armature 4 which is provided with a one way flexible pawl engaging the ratchet wheel N so that the latter becomes turned through one step. In the meantime the arm H has separated from the contact device 25 and disconnected contact strips 82 and 83. At this stage, whether the sender's arm L has already reached a corresponding position at the other end of the line or is still lagging the hair pin like member arriving first will be held waiting by the direct current solenoid until the slow acting electro-magnetic device 79 operates to close the switch 73 and the impulse thus produced at both or first at one then at the other end causes the element 205 to be displaced and to break the circuit at 201. Thus the commencement, the step-by-step movements during, and/or the ending of each swing, and the angular displacement of the drum, are synchronised. The switch 25 is flexibly mounted so that the part thereof which carries the contact strips 82 and 83 is slightly inclined to the plane of oscillation and a bent L-shaped projection carried by the arm H is able to contact with the contact strips 82, 83 on one side of the switch 25 when the hair-pin like member is moved to the right and with the contact strip 26 on the other side of the switch 25 when falling back under the action of gravity to the commencing position. Thus, when the hair-pin like member released by the electro-magnetic device 5 is falling back, the arm H engaging with

the drum P closes a circuit from one side of the line e. g. A through 205, 201, conductor 30, switch 86, drum P, arm H, contact 26 on the underside of 25 and back to the other side of the line. As mentioned above, the surface of the drum P is made up of insulating and conducting areas preferably flush with one another and with the rest of the drum, according to the outline of the signal to be transmitted and as the arm H passes from a conducting to an insulating portion and vice versa, impulses are formulated, said impulses actuating at the sender's and/or the receiver's end the relay comprising the ear piece and microphone device and the device incorporating the pointer c so that in turn the pointer 205 is caused to move and contact with the contact 202 which again enables a current to operate the electro-magnetic device G and to cause the markings to be produced upon the paper X. In this manner, X receives a series of markings corresponding in position from right to left with the position of the respective insulating and/or conducting areas provided on the sender's drum P, which are continued in successive lines with the step by step rotation of the respective drums.

Shortly before the hair pin like member reaches the end of its movement to the left, the solenoid 93 will be operated to raise the armature 32 which is now in proximity to the solenoid, to cause the contact to be broken at 25 and to displace the arm H beyond its normal position. When, however, solenoid 93 restores and permits the arm H to be restored to its former position of contact with strips 82 and 83 arm H will again serve to close the circuit through the electro-magnetic device F. I. If desired, the paper X may rest on a support so that the marker M is at a constant distance from X for ensuring the effective striking of the same irrespective of any variations in the diameter of the roll of paper.

It will be appreciated that the device incorporating the switch element 205 and the contacts 201 and 202 may comprise one or more rigid or flexible contacts for making and/or breaking and/or by-passing circuits. Also, more than one switch element 205 may, in some instances, be provided and arranged so that each functions under different conditions. For example, one such element may be provided and arranged so that it normally contacts with 201 when the bell is ringing and moving to contact 202 with the variations of the bell current and another such pointer may be provided and arranged so that it normally contacts with the contact 201 and moving to contact with its contact 202 with the formulation and reception of the signals after the bell has stopped ringing.

In Fig. 8 of the accompanying drawings there is shown a circuit arrangement which is similar in many respects to that shown in Fig. 7 and in which corresponding elements are denoted by corresponding references. In this arrangement, however, there is introduced a delay-action means adapted to afford the called subscriber when he is available, the opportunity of, or a longer period for, answering the call before the recording mechanism is brought into operation. Also, the said means may afford the calling subscriber the opportunity of hanging up his receiver before the termination of the ringing period. For the purpose of introducing such a delay a plurality of switches or oscillatory members is used and arranged so that for a period they operate in out-of-phase relationship and only when the said switches or oscillatory mem-

bers become in phase or otherwise coincide or co-operate will the circuit for initiating the operation of the recording means be completed. For example, the device 200 may be provided 5 with a further contact 210 arranged so as to be engaged by the switch element 205 at the time the latter contacts with the contact 202. Also, across the contacts 210 and 202 is arranged a circuit including a local battery 100 and an elec- 10 tromagnetically operable device 94 which, when actuated is adapted to attract one end 99 of a lever or pendulum device 97 mounted for movement about a pivot 95, the lower end of the said device being provided with a contact 103 for 15 engagement with another contact 96 connected with the slow release solenoid E. The lever or pendulum device is preferably provided with an adjustable or displaceable weight 97 so that its period of oscillation relatively to that of another 20 switch, pointer or lever, e. g. the element 205, can be varied. Thus, when the ringing or warning bell C is actuated, the element 205 will be swung into contact with the contacts 210 and 202 and local circuit through contact 210, bat- 25 tery 100, device 94 and other contact 202 will be completed, with the result that the electro-magnetic device 94 will be brought into operation to attract the upper end 99 of the lever or pendulum 97. The lower end 103 of the lever or pendulum is thus caused to engage with the contact 96 which is connected with the slow release relay E for establishing a circuit through E, 8, d, e, 15, 30 82, H, 83, 93 and the line B. It will be seen that the pivot 95 of the lever or pendulum 97 is in- 35 terconnected with the contact 202 and that it is not until the contacting of 202 and 205 coincides with the contacting of 103 and 96 that the relay E will be brought into operation to close the switches 86 and 98 for establishing the ap- 40 propriate D. C. circuits. Hence, by suitably vary- 45 ing the difference between the period of oscillation of the element 205 and that of the lever or pendulum device 97, the delay period can be in- creased or decreased. It will also be seen that, 50 in this arrangement, inter-action between the microphone 207 and the ear piece f is increased by the inclusion of an inductive coupling or transformer 108.

Having thus described this invention what I 55 claim as new therein and desire to secure by Letters Patent is:

1. A telephone system having a plurality of subscriber's stations each equipped with means for formulating and transmitting over the line 55 impulses constituting a recordable signal and recording means arranged to be brought into operation at a called subscriber's station for receiving and recording the signal of the calling subscriber, the said impulse formulating means and recording means comprising a double-armed member constituting an impulsive arm and a recording arm arranged for movement over the surfaces of a pair of rotatably mounted drums, one of the said drums being formed with con- 60 ducting and insulating areas contoured and ar- ranged for scanning by the impulsive arm to produce a predetermined signal and the other drum being equipped with a record element for cooperation with the recording arm, and the ar- 65 ranged being such that by the relative dis- placement of the drums and the double-armed member, the impulsive arm at the calling subscriber's station opens and closes the circuits for the transmission of the predetermined signal 70 75 while the recording arm at the called subscrib-

er's station is moved across and to and from the record element at the latter station to record the impulses transmitted.

2. A telephone system as claimed in claim 1 provided with electro-magnetically operable 5 means for effecting a step-by-step displacement of the double-armed members relatively to the drums at the calling and called subscriber's stations.

3. A telephone system having a plurality of 10 subscriber's stations each equipped with means for formulating and transmitting over the line impulses constituting a recordable signal and recording means arranged to be brought into operation at a called subscriber's station for 15 receiving and recording the signal of the calling subscriber, the said impulse formulating means and recording means comprising a double-armed member at each station, one arm of the double-armed member forming an impulsive arm and 20 the other arm forming a recording arm, each double-armed member being arranged for oscillatory movement relatively to the surfaces of a pair of drums, one of said drums being formed with conducting and insulating areas contoured 25 according to the characteristics of the signal to be transmitted and the other drum being equipped with a recording element with which the recording arm cooperates, and electro-magnetically operable means for imparting step-by-step 30 rotary movements to the drums at the end of each swing of the double-armed members.

4. A telephone system having subscriber's instruments equipped with means for formulating and transmitting over the line impulses constituting a recordable signal, which signal is characteristic of the telephone number of the calling subscriber, and recording devices arranged to be brought into operation during the absence of a 35 called subscriber for receiving and recording the signal of a calling subscriber, the said impulse formulating means comprising a contact member movable in relation to a displaceable element and the said displaceable element having parts of 40 differing electrical characteristics contoured 45 according to the nature of the signal to be transmitted, said subscriber's instruments being fitted with a sensitive pointer arranged in circuit with a receiver or ear piece disposed in close proximity with a microphone whereby pulsations received by the receiver affect the microphone to cause the pointer to move in sympathy with the impulses received for the purpose of setting up the circuits required for recording such impulses.

5. A telephone system having a plurality of subscriber's stations each equipped with means for formulating and transmitting over the line impulses constituting a recordable signal, the said impulse formulating means consisting of a contact member movable in relation to an angularly displaceable drum and the said drum being made up of relatively conducting and non-conducting areas contoured according to the nature of the signal to be transmitted, and recording devices 55 arranged to be brought into operation at a called subscriber's station for receiving and recording the signal of the calling subscriber, said subscriber's stations each being fitted with a sensitive pointer, a receiver or ear-piece arranged in 60 circuit with the sensitive pointer and a microphone disposed in close proximity with the receiver or ear piece whereby impulses received by the receiver affect the microphone to cause the pointer to move in sympathy with the impulses 65 70 75

received for the purpose of setting up the circuits required for recording said impulses.

6. A telephone system as claimed in claim 5 provided with a delay action means for introducing a delay in the setting up of the signal transmitting and receiving circuits.

7. A telephone system as claimed in claim 5 provided with a delay action means consisting of a plurality of oscillatory members arranged to 10 control the closing of the signal transmitting and receiving circuits, the arrangement being such that only when the said members are in phase will the circuits for initiating the actuation of the signal transmitting and receiving means be completed.

8. A telephone system having a plurality of subscriber's stations each equipped with means 20 for formulating and transmitting over the line impulses constituting a recordable signal, the said impulse formulating means consisting of a scanning device movable in relation to an angularly displaceable drum and the said drum being made up of relatively conducting and non-conducting areas contoured according to the nature of the 25 signal to be transmitted, and recording devices arranged to be brought into operation at a called subscriber's station for receiving and recording the signal of the calling subscriber.

9. In a telephone system, a calling station 30 including means for formulating and transmitting electrical impulses, said impulse-formulating means comprising a scanning device including a contact member, an angularly displaceable drum having on its surface a signal outline, said 35 signal outline being made up of relatively con-

ducting and non-conducting areas contoured according to the nature of the signal to be transmitted, means for causing the contact member to traverse the surface of the drum whereby each point on the surface of the drum is brought into contact with said contact member, means for transmitting over the line point-by-point impulses produced as the result of contact established between the contact member and the conducting parts of the signal outline, and a called station including means for sequentially recording said impulses to re-formulate point-by-point the signal outline provided at the calling station. 5

10. In a telephone system, a calling station 15 including means for formulating and transmitting electrical impulses, said impulse-formulating means comprising a scanning device including a contact member movable relatively to the surface of an angularly displaceable drum, said drum having on its surface a signal outline made up of relatively conducting and non-conducting areas contoured according to the nature of the signal to be transmitted, means for moving said contact member back and forth over the surface of the drum, means for rotating said drum to 20 bring each point of its surface in turn beneath the contact member, means for transmitting over the line point-by-point impulses produced by contacts sequentially established between the contact member and the conducting parts of the signal outline, and a called station including means for sequentially recording said impulses to 25 re-formulate point-by-point the signal outline. 30

GEORGE MICHAELSON. 35
